US00D984977S

(12) **United States Design Patent** (10) **Patent No.:** **US D984,977 S**
(45) **Date of Patent:** **** May 2, 2023**

(54) **WHITE NOISE MACHINE**

(71) Applicant: **Shenzhen Shouzheng Chuqi Technology Co., Ltd.**, Shenzhen (CN)

(72) Inventor: **Mengyi Sun**, Shenzhen (CN)

(**) Term: **15 Years**

(21) Appl. No.: **29/855,169**

(22) Filed: **Sep. 30, 2022**

(51) **LOC (14) Cl.** **14-01**

(52) **U.S. Cl.**

USPC **D14/216**; D24/231

CLAIM

The ornamental design for a white noise machine, as shown and described.

DESCRIPTION

FIG. 1 is a perspective view of a white noise machine showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

(Continued)

The dash-dash broken lines in the drawings depict portions of the white noise machine that form no part of the claimed design.

1 Claim, 8 Drawing Sheets
